UNITED STATES PATENT OFFICE.

HENRY ALLAN CLARK, OF OLD HARRY, MAGDALEN ISLANDS, QUEBEC, CANADA.

SHIPPING CRATE.

Application filed August 25, 1926, Serial No. 131,526, and Canada June 16, 1925.

This invention relates to improvements in shipping crates appertaining particularly to a device of this character designed for carrying live lobsters and wherein each is placed 5 in an individual compartment.

An object is to provide a shipping crate as described in which the compartments are T-shaped to freely yet economically receive a lobster, divided by screens to allow of the 10 circulation of water and yet keep the lobsters separated and lined with seaweed or the like to resemble as nearly as possible the natural surrounding in the ocean bed.

A further object is to provide a shipping 15 crate for live lobsters composed of a number of removable trays or layers of compartments that are T-shaped and so arranged that the tails or stems of inverted rows seat the confronting interstices.

20 A still further object is to provide a device of the character described wherein the number of parts are few, the construction simple and being capable of manufacture at a reasonable cost is thus rendered commercially desirable.

To the accomplishment of these and related objects that will become apparent as the description proceeds, the invention resides in the construction, combination and 30 arrangement of parts as shall be hereinafter more fully described, illustrated in the accompanying drawings and pointed out in the claims hereunto appended.

In the drawings, forming a part of this 35 disclosure: Fig. 1 is a plan of the crate with part of the cover broken away to show the interior arrangement and Fig. 2 is an end elevation the wall being similarly removed to disclose the contents.

40 In carrying out my invention, with a view to delivering a maximum percentage of live lobsters in perfect condition at their destination, I have provided this crate of economical construction and arrangement comprising only a perforated outer container of very ordinary design and tiers of trays 45 preferably of wire mesh subdivided into T-shaped compartments by like material. The subdivided trays comprise rows of parallel T-shaped cubicles, alternately inverted, so that the stems of confronting rows mesh with registering interstices occurring between the stems, thus providing individual compartments of a very desirable shape and so 50 formed that waste room is eliminated. By lining these with seaweed and like products

of the sea bottom, accommodation closely resembling his favorite haunts and indigenous quarters is provided the lobster which results in his delivery in the best possible condition. 60

Referring particularly to the drawings wherein like characters designate like parts throughout the several views, the box or casing is designated *a*. This comprises a container of wood or galvanized sheet metal and includes perforations *b* in sides, ends, top and bottom and also a hinged top *c* fastened when in closed position by the hasps *d*. 65

Trays *e* of wire mesh or other suitable material are disposed in tiers, within this container, and are subdivided into T-shaped compartments *f*. These are arranged parallel in inverted rows so that the confronting stems seat in the registering interstices formed thereby in the opposite row. The present embodiment illustrates two such pairs of adjoining rows and four trays thereof. 70

In shipping live lobsters these compartments will preferably be lined with seaweed and the like and when of reasonable dimensions will be found to be most desirable receptacles for such work due to their excellent configuration that prevents the lobster moving around and getting tangled up with himself or his fellows. 80

In use, the trays of cubicles will be lined and with the lowermost one reposing in the container the lobsters are packed therein, one in each compartment with its head and spreading claws in the cross head end and his tail extending down the stem. When the bottom tray is filled, the second tray is placed thereon in the crate thus closing any communication between compartments except for the water as will be hereinafter described that circulates through the screen. When the second tray is filled the third is applied and so on. The closing of the hinged top of the crate acts to isolate the cubicles in the top tray as did the superposing tray for those thereunder. 95

If it is desired to keep the lobsters in water during their trip the crates when closed and locked are placed in well bottom boats where they are submerged in sea brine and thus transported, the sea water finding access to the wire mesh apartments through the perforation in the crates. 100

105 From the foregoing description taken in connection with the accompanying draw-

ings, it will be manifest that a shipping crate is provided which will fulfill all the necessary requirements of such a device but as many changes could be made in the above description and many apparently widely different embodiments of my invention constructed within the scope of the appended claims without departing from the spirit or scope thereof, it is intended that all matters contained in the said accompanying specification and drawings shall be interpreted as illustrative and not in a limited sense.

Having thus described my invention, what I claim as new and desire to secure by Letters Patent is,—

1. A shipping crate for live lobsters comprising a casing and a tray subdivided into parallel T-shaped compartments matching so as to employ all the space in the tray with the exception of two half compartment spaces at either end of the tray.

2. A shipping crate for live lobsters comprising a casing and tiers of removable trays that are subdivided into reversed parallel rows of T-shaped compartments matching so as to employ all the space in the tray with the exception of two half compartment spaces at either end of the tray.

3. A shipping crate for live lobsters comprising a ventilated casing with a removable cover and a plurality of trays subdivided into interspaced parallel T-shaped compartments matching so as to employ all the space in the tray with the exception of two half compartment spaces at either end of the tray.

4. A shipping crate for live lobsters comprising an outer ventilated casing and subdivided wire screen trays subdivided into interspersed rows of parallel T-shaped compartments matching so as to employ all the space in the tray with the exception of two half compartment spaces at either end of the tray.

5. A shipping crate for live lobsters comprising an outer ventilated casing, a removable closure therefor and tiers of wire screen trays subdivided into parallel rows of interspaced T-shaped open topped compart-

ments matching so as to employ all the space in the tray with the exception of two half compartment spaces at each end of the tray.

6. A shipping crate for live lobsters comprising an outer ventilated casing, a hinged closure therefor, and tiers of trays each subdivided into parallel rows of T-shaped compartments matching so as to employ all the space in the tray with the exception of two half compartment spaces at either end of the tray, the several compartments of each tray having open tops which are closed by the bottom of the superposed tray while the compartments of the top tray are isolated by the hinged closure when same is in closed position.

7. In a shipping crate for live lobsters, a tray comprising a pair of inverted rows of interspaced parallel compartments of uniform size and shape of corresponding irregular outline and matching so as to employ all the space in the tray with the exception of two half compartment spaces at each end of the tray.

8. In a shipping crate for live lobsters, a tray comprising a pair of alternately inverted rows of interspaced T-shaped compartments, in either half thereof and matching so as to employ all the space in the tray with the exception of two half compartment spaces at either end of the tray.

9. In a shipping crate for live lobsters, a plurality of trays each comprising two pairs of parallel rows of T-shaped compartments whose inturned stems fill the alternate interstices formed between the stems of the adjoining row of T's by the contacting of the cross heads thereof.

10. A shipping crate for live lobsters, comprising an outer ventilated casing and tiers of wire mesh trays subdivided into opposed parallel rows of T-shaped lobster-receiving compartments matching so as to employ all the spaces in the tray with the exception of two half compartment spaces at either end of the tray and lined with seaweed.

In testimony whereof I hereunto affix my signature.

HENRY ALLAN CLARK.
